(No Model.)

C. W. CLARK.
PLOW.

No. 434,245.

Patented Aug. 12, 1890.

UNITED STATES PATENT OFFICE.

CHESTER W. CLARK, OF MISHAWAKA, INDIANA.

PLOW.

SPECIFICATION forming part of Letters Patent No. 434,245, dated August 12, 1890.

Application filed November 1, 1889. Serial No. 328,970. (No model.)

To all whom it may concern:

Be it known that I, CHESTER W. CLARK, of Mishawaka, St. Joseph county, in the State of Indiana, have invented new and useful Improvements in Wheeled Plows; and I do hereby declare that the following is a full and accurate description of the same, reference being had to the accompanying drawings, wherein—

10 Figure 1 is a perspective view of my plow in operative position. Fig. 2 is a perspective view of the controlling-gear enlarged from Fig. 1. Fig. 3 is a perspective view of the leading furrow-wheel gear enlarged from Fig. 1, the tongue-latch being thrown back out of engagement. Fig. 4 is a section showing the tongue-latch in engagement to lock the tongue. Fig. 5 is a sectional elevation of a lock for the caster-colter. Fig. 6 is a plan of the land-15 wheel mounting and the leading furrow-wheel gear. Fig. 7 is a perspective view of an adjustable mount for the leading furrow-wheel gear, whereby said leading-wheel may be set to gage the width of the furrow. Fig. 20 Fig. 8 is a perspective view showing the action of the automatic lock.

The principal objects of my invention are, first, to lighten the plow by dispensing with the weight of the wheel-frame, &c., which is 25 usually employed with plows of this class; second, to adapt the plow to turn a corner squarely or run a furrow straight with equal facility by making the caster furrow-wheels to lock and unlock automatically, according 30 as the plow runs a straight furrow or turns at a corner; third, to lock the colter when running a straight furrow to steady the plow; and, fourth, to apply a parallel movement to the leading furrow-wheel, whereby as it is 35 raised or lowered its caster-spindle will remain vertical.

A is the plow, and B is its beam, both of suitable style and material. In practice I have used steel beams satisfactorily. The 40 furrow-wheel C is mounted as a caster-wheel at the extremity of the arm D, which is fastened to the beam by means of a cast-iron shoe and clip E. The land-wheel F is on the extremity of the crank-axle G, which is mounted 45 in bearing-boxes H, which are secured opposite the middle of the beam, one to the beam itself and one at the extremity of the

bracket I, which is bolted to the beam. The inner extremity of the axle G projects from its box H and is provided with the collar J, 55 which is rigidly attached to said axle. The levers K L are mounted on said axle as a center. The spring M is attached at one end to the collar J, and at its free end it is attached to the lever L, so that its tension is 60 always exerted to throw said lever forward and to depress the land-wheel F. When said lever is locked in position, the weight of the machine, together with the weight of the driver, so far as the same rests on the land- 65 wheel, tends to depress the machine, and is in effect the same as a tendency to raise the wheel. This tendency is resisted by the spring M, and the resiliency of said spring, together with the inertia of the machine and rider, permits said land-wheel to rise under sudden pressure, as in passing over an obstruction, 70 without affecting the level of the plow.

The tension of the spring M may be changed in various ways, but conveniently by causing it to approach or recede from the collar J at its extremity or point of attachment by means of a bolt P or some similar means.

The lever L is provided with an ordinary lock-bolt Q (shown in dotted lines in Fig. 2) 80 and a segment-rack R, so that by adjusting said lever forward or backward the wheel F may be raised or lowered, according as the plow is in the ground, or is raised above it for transportation.

When the plow is to be moved from place to place, it is important that the share should be raised above the ground, and this is done by depressing the land-wheel F and the leading furrow-wheel S, which has its housings 90 attached to the beam B near its forward end. The "set" of the plow is also regulated as to depth of plowing by the elevation or depression of the leading furrow-wheel, and whatever may be its elevation it is important that 95 its caster pivot or spindle shall remain vertical. I have therefore attached the "parallel" rod T above the crank-axle U, upon which the caster-pivot V and its sleeve-box W is carried. The required parallelism may be attained by means of a series of levers coupled together and fulcrumed on the beam by means of a train of segment-gears centered on the beam and by other known mechanical expe- 100

dients, which do not require particular description here, because after calling attention to the desirability of it and one way of accomplishing it any skilled mechanic will be able 5 to supply other ways.

As shown in the drawings, the tubular bracket *a* is bolted to the side of the beam and is provided at its outer end with the vertical arm or stud *b*. The inner end of the 10 crank-axle rod *U* passes through said tubular bracket and has attached to it the lever *C*, and this lever is connected with the hand-lever *K* by means of the rod *d*. The lever *K* is provided with a lock-bolt and segment- 15 rack *e*, as is common, and by it the position of the leading caster-wheel *S* is adjusted and controlled. The spindle *V*, upon which the caster-wheel arm *f* swivels, is carried by the sleeve *W*, through which the crank-rod 20 *U* passes. Said sleeve is provided with a stud or arm *g*, and the parallel rod *T* is attached at one end to said stud *g* and at the other end to the corresponding stud *b*.

When the plow is running straight, as in 25 turning a furrow, it is advantageous to have the leading and trailing furrow-wheels restrained from swinging on their caster-pivots, as it tends to steady and hold the plow to its furrow; but when turning at the corner of the 30 land it is necessary that said wheels shall be free to swing, because one or the other of said wheels would otherwise be compelled to drag on the ground. I have therefore provided a lock whereby said wheels may be retained in 35 plane of advance when the plow is moving on a straight line and permitted to swing when the plow is turning at the corner, and to avoid the inconvenience of attention to this locking and unlocking I have preferred to make the 40 same automatic by means of the locking-tongue *h* on the collar *i*, the same having inclined sides and fits into a corresponding notch in the hub of the arm *f*. When in action, the weight of the machine, the driver, 45 and the load of earth on the plowshare is sufficient to keep the locking-tongue in its notch with sufficient force to maintain the wheels in plane; but when there is a change of direction of advance the leverage of the 50 wheel-arms *f* is sufficient to force the tongues out of the notches, as shown by dotted lines in Fig. 2 and by full lines in Fig. 8, and the wheels may then swing free until the machine comes again into the plane of advance. The 55 colter *K* is made to swing for the same reason; but when the machine is moving in a straight line it is better that the colter shall be held rigidly in the plane of advance, and for that reason I also provide it with a lock, which 60 may be automatic or positive, as preferred. In Fig. 5 I have shown a positive locking-bolt *m*, controlled by a spring *n* in one direction and the foot-lever *p* in the other direction.

A tongue is desirable to aid in controlling 65 the plow while being transported and in backing the plow, if for any reason it shall be necessary. While passing along the road and in

backing the plow, the tongue requires to be fixed against lateral movement as to the machine; but in turning corners, &c., and in 70 regular plowing it requires to be free to move laterally, and sometimes it is desirable to dispense with the tongue entirely. To meet all these conditions, I attach to the front end of the beam a vertical tubular post *q*, and I provide a tongue-plate *r* with a spindle *s* to enter said tubular post, as shown in Figs. 3 and 75 4. The tongue is hinged to said tongue-plate for movements in a vertical plane and is free to swing laterally on the spindle *s*, while it 80 may be readily removed entirely by lifting said spindle out of the tubular post. A latch *t* is attached to the tongue-plate, and when the tongue is to be free said latch is thrown over back or otherwise removed from engagement, 85 and when the tongue is to be restrained from lateral movement said latch is thrown over forward into engagement with some proper part or attachment of the post *q*. In Fig. 4 the latch is shown in such engagement. 90

It is sometimes desirable to vary the width of the furrow, and as this width may be determined and gaged by the leading furrow-wheel it may therefore be made adjustable as to its distance from the beam, and to this 95 end I find it convenient to make the sleeve-box *a* separate from its supporting bracket and movable endwise thereon. It may be clamped fast in the desired position by a clip *u* or other convenient device, substantially as shown in 100 Fig. 7.

Having described my invention, I claim—

1. In a wheeled plow, a leading caster-wheel, a pivoted supporting-arm whereby said wheel may be raised or lowered, and means whereby 105 the caster-spindle of said wheel may be automatically maintained in an operative position at all levels.

2. In a wheeled plow, a front caster-wheel *S* and its sleeve-box *W*, provided with the 110 stud *b*, the crank-rod *U*, and the sleeve whereby said crank-rod is supported, provided with the stud *b*, combined with the parallel rod *T*, for the purpose set forth.

3. A wheeled plowing-machine provided 115 with a mold-board plow, the caster furrow-wheel, and an automatic gravity-lock for the same consisting of a tongue *h* and corresponding recess in a flat surface so related that said tongue is forced into said recess and 120 retained therein by the gravity of the plow, added to the weight of the driver and the load carried by the mold-board, to hold said wheel in position while the plow is advancing in a straight line and automatically release 125 the same by the riding of said tongue out of said recess and upon said flat surface when the plow turns at the corner.

4. In a wheeled plow, a caster-colter, combined with means controllable at will by the 130 driver on his seat, whereby said colter may be locked against lateral swing on its caster-pivot or permitted to swing freely, as desired.

5. In a wheel-plow, a caster-colter, with a

socket-plate attached to the beam, and the pivot for said colter working in the socket thereof, combined with a locking-bolt *m*, adapted to engage and lock the swinging colter-arm, and a lever whereby said bolt may be lifted out of action at will.

6. In a wheeled plow, a tongue hinged to the beams thereof to move vertically and laterally, combined with the latch *t*, hinged to the tongue-plate and adapted to engage with some proper part connected with the beam, substantially as set forth.

7. In a wheeled plow, a hollow post *q*, rigidly attached to the front end of the beam, combined with the tongue-plate *r*, provided with the spindle *s*, adapted to enter said post, whereby the tongue is rendered readily detachable, as set forth.

8. In a wheeled plow, the yielding crank-
20 axle *G*, having the land-wheel *F* hung on the crank end, combined with the collar *J*, rigidly attached to the opposite end of said axle, the tension-spring *M*, and the hand-lever *L*, for the purpose set forth.

25 9. In a wheeled plow, the yielding crank-
axle *G* to carry the land-wheel, the collar *J*, rigidly attached to said axle, the spring *M*, and hand-lever *L*, combined with the tension-bolt *P*, whereby the tension of said spring
30 may be varied, as set forth.

10. In a wheeled plow, a caster furrow-wheel

mounted on a crank-rod *U*, whereby said wheel may be raised or lowered, combined with the sleeve-box *W*, made separate from the support for the spindle *V*, said spindle 35 being adjustable on said sleeve-box *W*, substantially as set forth.

11. In a wheeled plow, the combination of the following members, viz: a beam-frame having a mold-board plow attached thereto, 40 the caster furrow-wheels, the automatic gravity-locks for said wheels, and parallel members for the leading caster-wheel, as set forth.

12. In a wheeled plow, the combination of the following members, viz: a beam-frame 45 having a mold-board plow attached thereto and a caster-colter, a lock for the same, a tongue hinged for vertical and lateral movements, a latch to lock said tongue against lateral movement, a crank-axle and land-wheel carried thereon, a hand-lever to control said crank-axle, and a spring *M*, attached to and coiled around the axis of said axle, as set forth.
